UNITED STATES PATENT OFFICE.

HERMAN C. PRIEBE, OF BRADFORD, ILLINOIS.

DRAFT-RIGGING.

SPECIFICATION forming part of Letters Patent No. 740,779, dated October 6, 1903.

Application filed March 30, 1903. Serial No. 150,264. (No model.)

To all whom it may concern:

Be it known that I, HERMAN C. PRIEBE, a citizen of the United States, residing at Bradford, in the county of Stark and State of Illinois, have invented a new and useful Improvement in Draft-Riggings, of which the following is a specification.

My object is to provide a draft-rigging adapted more especially for freight-cars and of an improved construction which renders it particularly simple, strong, and durable and well adapted for all requirements, also easy to place in position and to inspect.

Referring to the drawings, Figure 1 is a broken plan sectional view of my improved draft-rigging at one end of a car, the springs at one side being shown in elevation and those at the opposite side in section; and Fig. 2, a broken partly-sectional side elevation.

For convenience I show my improvements applied to a car of steel construction, though the invention is not to be limited thereto.

A indicates one of the end sills of a freight-car, and B B longitudinally-extending center sills. These center sills in the construction shown are steel channel-beams, as is usual in steel constructions, and form in themselves the draft-plates. Riveted, preferably, against the outer faces of the center sills in the channels thereof are reinforcing plates C C of desired length. Extending through the center sills and their reinforcing plates in the positions shown are forward slots a and rear slots b, elongated in the direction longitudinally of the sills.

D is a draw-bar having a neck portion D', movable in the usual way through a sustaining-guide in the end sill A, and a stem portion D''. In the stem portion are the forward and rear openings c d, corresponding in size approximately with the openings a b. Extending through the forward openings a c of the sills and draw-bar is a forward follower or bar E, and a similar rear follower or bar F extends through the openings b d of the center sills and draw-bar. The bars E F extend a suitable distance beyond opposite sides of the center sills.

G G are inner coiled springs at the outer sides of the sills C and having looped ends e, arranged to fit over the end portions of the bars E F. Between the coiled portions of the

said springs and the bars or followers E F are preferably flanged or cup-shaped disks or washers f, having perforations through which the end portions of the springs pass, which operate to maintain the disks or washers in place. Between the disks or washers f at each side are outer coiled springs H, confined at their ends in the cups afforded by the disks. The springs are held against removal by cotters or the like g passing through the bars, as shown. The springs H G fit tightly between the disks or washers f and operate normally to maintain the bar E at the forward ends of the slots a c and the bar F at the rear ends of the slots b d.

A pull upon the draw-bar D causes it to bear against the rear bar F and compress the springs against the bar E, which remains stationary, while the draw-bar may travel forward a distance equal to the length of the slots c b. Backward pressure against the draw-head causes the draw-bar to bear against the forward bar or follower E and force it backward in the slots a to compress the springs. In this movement of the draw-bar the follower E moves in the slots a, while the bar F remains stationary, permitting the draw-bar to move in the backward direction a distance equal to the length of the slots d a.

The plates C operate to reinforce the sills at the slots. It will be seen that the parts are so arranged that they may be readily placed in position or removed. The springs G H are in exposed positions, so that they may be readily inspected, and in the event that one of them becomes broken it is an easy matter to remove the cotters g, slip the springs from the followers, and replace with new springs. The construction permits the employment of a very strong and durable draw-bar, and the pull thereon is resisted by the followers E F, which, being placed to resist the strain edgewise, are especially strong. When the movement of the draw-bar produces complete compression of the springs, both the followers rest against rigid stops at the ends of the slots a b, and thus they both operate to resist the strain. The draw-bar therefore cannot be drawn out or displaced, even in the event that the springs or one of the followers should be broken.

It is desirable to have the draft-plates or

center sills B near together to shorten the distance between them and the sides of the draw-bar. This contributes materially to the power of resistance of the followers against 5 breaking in the space between the draw-bar and draft-plates. Where the draft-plates are rather far apart, as indicated in the drawings, guide-blocks I may be suitably fastened against the inner faces of the draft-plates as 10 indicated, to limit the side play of the draw-bar and keep it always near the center.

While I prefer to construct my improvements throughout as shown and described, they may be variously modified in the matter 15 of details without departing from the spirit of my invention as defined by the claims.

What I claim as new, and desire to secure by Letters Patent, is—

1. In a draft-rigging, the combination of 20 draft-plates having elongated forward and rear openings, a draw-bar having a solid integral stem portion provided with forward and rear openings corresponding with said openings in the draft-plates, forward and rear follower-bars extending through the said forward and rear openings in the draw-bar and draft-plates to slide therein in the direction longitudinally of the car, and coiled springs 25 confined between and bearing at the opposite ends of their coils against said follower-bars at the outer sides of the draft-plates.

2. In a draft-rigging, the combination of 30 draft-plates having elongated forward and rear openings, a draw-bar having a solid integral stem portion provided with forward and rear openings corresponding with said openings in the draft-plates, forward and rear follower-bars extending through the said forward and rear openings in the draw-bar and 35 draft-plates to slide therein in the direction

longitudinally of the car, and coiled springs confined between and bearing at the opposite ends of their coils against said follower-bars at the outer sides of the draft-plates and removably connected at their opposite ends with 45 the follower-bars.

3. In a draft-rigging, the combination of draft-plates having forward and rear openings, a draw-bar presenting corresponding forward and rear openings, follower-bars extending through the said forward and rear openings in the draw-bar and draft-plates to slide therein in the direction longitudinally of the car, coiled springs confined between the said follower-bars at the outer sides of the 50 draft-plates and having looped ends fitting over said bars and removable pins extending through openings in the end portions of the follower-bars for holding the springs in place.

4. In a draft-rigging, the combination of 55 draft-plates having forward and rear openings, a draw-bar presenting corresponding forward and rear openings, follower-bars extending through the said forward and rear openings in the draw-bar and draft-plates to 60 slide therein in the direction longitudinally of the car, inner coiled springs between said follower-bars at the outer sides of the draft-plates having looped ends fitting over said follower-bars, removable pins confining the 65 said looped ends against sliding from the follower-bars, washers upon the said looped end portions of the inner springs bearing against the said follower-bars, and outer coiled springs 70 confined between the said washers.

HERMAN C. PRIEBE.

In presence of—

A. C. KITTLESON,
M. S. MACKENZIE.
